UNITED STATES PATENT OFFICE.

EMIL ZILLING, OF LEIPZIG, GERMANY, ASSIGNOR TO JAMES G. PRAGER AND HUGO PRAGER, DOING BUSINESS AS THE PRAGER CO., OF NEW YORK, N. Y.

DESIGN FOR WALL-PAPER.

40,547.

Specification for Design.

Patented Feb. 22, 1910.

Application filed December 27, 1909. Serial No. 535,211. Term of patent 7 years.

To all whom it may concern:

Be it known that I, EMIL ZILLING, a subject of the German Emperor, and resident of Leipzig, Germany, have invented a new, original, and ornamental Design for Wall-Paper, of which the following is a specification.

Reference is to be had to the accompanying drawing illustrating a face view of a section of wall paper, in which my new design has been embodied.

The design comprises a series of adjacently arranged columns of parallel lines of varying degrees of thickness and of varying

degrees of light and shade. The lighter lines in one column are arranged adjacent to the heavier lines of the adjacent columns so that the finished design produces a silky effect. Between each two columns of parallel lines is arranged a series of spaced circles or dots.

I claim:

The ornamental design for wall paper as shown and described.

EMIL ZILLING.
